United States Patent Office

Des. 217,521
Patented May 5, 1970

217,521

HEADBAND

Ray F. Shores, 1930 Searles Road,
Baltimore, Md. 21222

Filed Jan. 30, 1968, Ser. No. 10,366

Term of patent 14 years

Int. Cl. D3—99

U.S. Cl. D86—10

FIG. 1

FIG. 2

FIG. 1 is a front perspective view of a headband showing my new design;

FIG. 2 is a front perspective view in wearing position, the broken line showing of the wearer's head being for purposes of illustration only.

The drawing has been lined for color.

I claim:

The ornamental design for a headband, as shown and described.
